AUGUST HUND, OF WEST ORANGE, NEW JERSEY, ASSIGNOR TO WIRED RADIO, INC., OF NEW YORK, N. Y., A CORPORATION OF DELAWARE

SIGNALING SYSTEM

Application filed October 1, 1931. Serial No. 566,229.

My invention pertains in general to signaling systems and specifically relates to a system for effecting the key modulation of high frequency oscillations.

5 In my co-pending application, Serial Number 561,837, filed September 9, 1931, and entitled, "Oscillation generator", I have disclosed a system for developing high frequency oscillations from relaxation oscillations produced by a glow discharge tube.

10 The principal object of my present invention consists in providing a relaxation oscillation circuit for producing high frequency oscillations for keying modulation purposes.

15 Another object consists in producing a relaxation system for developing high frequency oscillations which are signal modulated by oscillations produced by another relaxation circuit.

20 I accomplish these and other desirable objects in a novel signaling system employing a glow discharge tube and associated circuits for producing high frequency oscillations which are modulated by relaxation oscillations produced by another glow discharge tube and associated circuit.

25 In the drawing accompanying and forming a part of this specification I have diagrammatically represented one embodiment 30 of the signalling system in my invention showing a preferred arrangement of the circuits.

35 Referring to the drawing in detail there is provided a glow discharge tube 1 which 40 comprises a tubular envelope enclosing a pair of electrodes 2 and 3. In the present embodiment of my invention this envelope is provided with an attenuated atmosphere of helium. I have found that satisfactory results can be obtained by maintaining this atmosphere of helium at a pressure of substantially 12 mm. of mercury. It will be understood that other suitable gases can be used in lieu of helium and at other suitable pressures. The electrodes 2 and 3 are of a small area and disposed longitudinally of the envelope 1 to form a small gap between the electrodes in a manner such as to reduce inter-electrode capacitance to a minimum. A tubular metallic control electrode 4 is exter-

nally positioned on the envelope 1 in a position encircling the gap between the ends of the two electrodes 2 and 3. The electrode 4 serves to electrostatically control or modulate the ionization discharge between electrodes 2 and 3 in the glow discharge tube 1 as hereinafter described.

55 The electrodes 2 and 3 are connected with an external circuit including a resistance 5, and a source of direct current 6 connected in series. Connections from the electrodes 2 and 3 are further extended to include a circuit having an inductance 9 and capacitance 10 connected to form a closed circuit in series with the variable condenser 8, as shown. The 60 inductance 9 is electromagnetically coupled to an inductance 11. The inductance 11 is connected in series with a capacitance 12 and load 13 to form a resonant circuit tuned to a desired high frequency suitable for carrier 65 transmission purposes and designated as the frequency f_1 . The load 13 is indicative of any work circuit for the utilization of signal modulated high frequency currents, such as an antenna system.

70 In accordance with my invention, there is provided another glow discharge tube 15 comprising an envelope enclosing a pair of electrodes 16 and 17. The envelope 15 is provided with an attenuated atmosphere of helium at a pressure of substantially 12 mm. of mercury similar to the glow discharge tube 1. The electrodes 16 and 17 are disposed in a manner such as to reduce inter-electrode capacitance to a minimum. These electrodes 80 75 85 90 95 100 16 and 17 are connected with an external circuit including a resistance 18, a source of direct current 19 and an inductance 20, all connected in series. A variable condenser 14 is connected in shunt with the electrodes 16 and 17. The inductance 20 comprises the primary winding of an audio frequency transformer having a secondary winding 21. The secondary winding 21 is connected with a key 22 of that type having two contacting members, such as contacting members 23 and 24, for simultaneously opening both sides of a circuit, such as the circuit between the control electrode 4 and electrode 3 of glow discharge tube 1. The actual construction of

the key 22 is well-known in radio signaling and for that reason is only diagrammatically represented in the drawing.

In the operation of my signaling system, 5 the source of current 6 applies a potential difference to the electrodes 2 and 3 which is of a magnitude sufficient to initiate a glow or ionization discharge. The voltage necessary to bring about this glow discharge will be 10 called the ignition voltage. If the resistance 5 is of a proper value, the glow discharge which takes place across the electrodes 2 and 3 will produce a potential drop across the resistance 5, whereby the voltage across the 15 electrodes 2 and 3 will become reduced. As soon as the voltage across the electrodes 2 and 3 becomes smaller than the lower critical voltage, the glow discharge will be 20 quenched. The foregoing functions will be 25 repeated to produce continuous relaxation oscillations of a fundamental frequency designated as f_0 .

These relaxation oscillations produced by 30 the glow discharge tube 1 and associated circuit produce impulse energization of the circuit 9-10. The circuit 9-10 has parameters of a value such that this impulse energization will set up oscillatory currents at frequencies which will be integral multiples of the fundamental frequency f_0 of the relaxation oscillations. The resonant circuit including the inductance 11 and capacitance 12 is tuned to a desired high frequency f_1 which is a particular integral multiple of the fundamental 35 relaxation frequency f_0 . The frequency f_1 appears in the resonant circuit 9-10 and is selected by the circuit 11-12 for effecting the transfer of oscillations at the desired frequency f_1 to the load 13.

40 Further in the operation of my signaling system, the source of direct current 19 applies a potential difference to the electrodes 16 and 17 which is of a magnitude sufficient to initiate a glow or ionization discharge in the tube 45 15. This glow discharge which takes place across electrodes 16 and 17 will produce a potential drop across the resistance 18 whereby the voltage across the electrodes 16 and 17 will become reduced. As soon as this 50 voltage reduction occurs the glow discharge will be quenched. The foregoing functions will then be repeated to produce continuous relaxation oscillations of an audible frequency f independently of the frequencies f_0 or f_1 . These oscillations of the frequency f produced by the glow discharge tube 15 act 55 through winding 20 to induce electromotive forces in winding 21. When the key 22 is closed, a circuit will be completed to control electrode 4 whereby these electromotive forces induced in the winding 21 will serve to produce an electrostatic field to modulate or control the ionization discharge of glow tube 1 in accordance with the audible frequency f of the glow discharge tube 15 and 60

associated circuit. The high frequency oscillations of the frequency f_1 appearing in circuit 11-12 and transferred to load 13 will therefore be audibly modulated for a duration depending upon the period of time that key 22 is manually closed. Thus, the key 22 can be manipulated to produce signal modulation in accordance with any desired code as is common in radio signaling.

70 Although I have shown a preferred embodiment of my radio signaling system it will, of course, be understood that changes can be made therein without departing from the intended scope of my invention. I do not therefore desire to limit myself to the foregoing except insofar as may be pointed out in the appended claims.

80 What I claim as new and original and desire to secure by Letters Patent of the United States is:

85 1. A signaling system comprising, an oscillation circuit for producing high frequency oscillations, a selection circuit coupled to said oscillation circuit, said selection circuit being tuned to a desired high frequency, a 90 relaxation circuit for recurrently energizing said oscillation circuit at a frequency which is an aliquot part of said desired frequency, a source of audible frequency oscillations, and means for selectively connecting said source of audible frequency oscillations with said relaxation circuit for effecting the modulation of said oscillations of said desired high frequency by said audible frequency oscillations.

95 100 2. A signaling system comprising, an oscillation circuit for producing high frequency oscillations, a selection circuit coupled with said oscillation circuit, said selection circuit being tuned to a desired high frequency, a relaxation oscillation circuit for recurrently energizing said oscillation circuit at a frequency which is an aliquot part of said desired frequency, said relaxation oscillation circuit including a glow discharge tube having an 110 external control electrode, a resistance, and a source of direct current all connected in series; another relaxation oscillation circuit including a glow discharge tube, a resistance, and a source of direct current connected in 115 series; and a keying circuit connected with said control electrode, said keying circuit being inductively coupled with said second mentioned relaxation oscillation circuit.
